DISPENSER

Orval I. Kight, Ralston, Nebr., assignor of one-half to Frank Lindee, Omaha, Nebr.

Application June 29, 1936, Serial No. 87,937

2 Claims. (Cl. 221—98)

This invention relates to containers such as or similar to those adapted for the transportation and merchandising of granular substances such as coffee, soap chips and the like and more particularly to a container for said substances which may be manipulated with one hand while held in said hand for dispensing a predetermined measured quantity of substance from the package or container.

10 It is an object of the invention to provide means for preventing waste of substances which as heretofore practiced have been dissipated through pouring or procuring a larger amount thereof from a container than is sufficient for a certain purpose or immediate use.

Another object of the invention is to provide a container for said useful purposes which is economical in construction and efficient in use.

Other objects and advantages of the invention 20 will be more fully described hereinafter and will be more particularly pointed out as claimed herein.

In the drawing wherein like symbols refer to like or corresponding parts throughout the several views:

25 Figure 1 is a vertical section of a portion of a container showing an embodiment of the present invention in connection therewith, the measuring device thereof being in an open or material discharge position.

Figure 2 is an end view of a portion of the container shown in Figure 1, said measuring and discharge portion being illustrated in a folded and sealed position.

30 Figure 3 is a view similar to Figure 2 but illustrating the appearance of the container after a sealing tongue preferably employed has been removed from the device.

Figure 4 is an end view of the device shown 40 in Figure 1, the discharge chute thereof being in an open position.

Figure 5 is a semi-diagrammatic view illustrating a measuring of a substance into the discharge chute prior to a discharge thereof.

45 Figure 6 illustrates a discharge of said substance through said chute.

Figure 7 is a top plan view of the invention on a reduced scale.

As heretofore practiced in the art cardboard 50 packages or containers having, for instance, soap chips therein have been used by a housewife, during washing dishes, by employing the expedient of tearing or punching a hole through the top of the package and then shaking the chips 55 into the dish water pan, said holes being of va-

rious sizes and the contents of the containers being poured therefrom for various periods results in either not enough chips being dispensed to cause sufficient suds in said water or that too much chips are dispensed in a wasteful manner 5 and the present invention comprehends the provision of means for preventing the disadvantageous practices of the prior art.

Referring now to the drawing for a more particular description, the numeral 10 indicates a 10 container such as is formed of folded cardboard or any suitable material folded or otherwise. The container 10 may be of any size or shape and if of rectangular construction is formed with six closure walls providing a box-like structure including a top 11 through which, during the manufacture thereof and adjacent a corner or edge of the container 10 is provided with an aperture 12.

The aperture 12 may be of any desired size 20 or configuration and is of a preselected size in accordance with the merchandise or ingredients which are to be packaged in the container. Coarse substances such as soap chips require a much greater aperture 12 than finer merchandise such as, for instance, ground coffee.

25 During manufacture the container 10 is provided with a discharge chute which is preferably made of paper and secured to three side walls of the container 10 or may be formed integral with said walls or comprising a continuation thereof and in the specific embodiment of the invention depicted in the drawing the discharge member 13 includes, as shown in Figure 1, an end wall 14 adjacent said aperture, oppositely disposed side walls 15 and a cover 16, whereby the chute overlies the aperture 12 and an elongated recess 17 is provided between the cover 16 and the top 11 of the container having an open end 18 which is oppositely disposed with respect to the end 40 wall 14, said parts in use being arranged as shown in Figure 1.

30 In operation the device is grasped between the thumb and forefinger and tilted in a direction whereby the elongated recess 17 of the chute is swung vertically and the end wall 14 lowered or raised with respect to the open discharge end 18 of the device as shown in Figure 5 or the device may be, if desired, turned upside down or inverted in accordance with the quantity of material remaining in the device, whereby a portion 45 of the contents of the package or device may thereby be caused to move through the aperture 12 as shown in Figure 5, the quantity so moved through said aperture being predetermined by 50

the size of said aperture. The device is now swung in a reverse direction or rotated, whereby the end wall 14 is then positioned higher than the discharge spout 18 of the device, permitting the predetermined and measured quantity of the ingredients to slide outwardly of the end 18 through the elongated recess 17 and the walls of said recess guide and direct the ingredients toward the dish pan, coffee pot or the like. At 10 times when the device is nearly emptied the recess 17 is held downward with respect to other portions of the invention for discharging a measured portion therethrough and the open end 18 is held lowermost during said discharge.

15 Assuming that the ingredients to be dispensed are soap chips and a dish pan having a large amount of water is being employed the housewife may repeat the said operation for discharging from the device a second predetermined quantity 20 of soap chips sufficient to form suds in an economical manner. Similarly and assuming that ground coffee is being discharged and that the size of the aperture 12 is sufficient only to permit enough coffee grounds for one cup of 25 coffee to be discharged for each oscillation of the device and further assuming that six cups of coffee are desired, the operator may economically discharge the proper amount of ground coffee into the coffee pot without waste and in accordance 30 with the direction of the vender of the coffee with respect to his recommendation as to the quantity of coffee sufficient to provide a cup of coffee of ordinary strength.

When not in use the cover 16 and side walls 15 35 may be folded for preventing air from entering the interior of the package such as may be calculated to deteriorate the aroma of the coffee upon contact with the latter and similarly would dry soap chips.

40 At the time the device of the present invention, containing the merchandise, leaves the factory the container is hermetically sealed and remains so while on the shelves of the retailer, said cover 16 together with the oppositely disposed side 45 walls 15 and the end wall 14 being folded inwardly and in abutting relation with respect to the top 11 as shown in Figure 7 and at this time the cover 16 is provided with a tongue 19 which extends over the end wall of the main body portion of the container 10 adjacent the open end 18 of the elongated recess 17 to seal the latter, said tongue being provided with a tang 20 which is caused to adhere to the container by means of a suitable adhesive whereby the interior of the 55 container 10 is hermetically sealed.

55 In use the consumer may insert his thumb nail, the blade of a case knife or any suitable media under the tang 20 for freeing it from the adjacent wall of the container 10; whereupon 60 the tang is grasped between the thumb and forefinger and the tongue 19 moved into alignment with the cover 16; whereupon said tongue 19 may, if desired, be torn off from the cover 16, whereby the appearance of the device would be 65 changed from its distribution appearance depicted in Figure 2 to its appearance while in use or the form shown in Figure 3, the tongue 19 being removed during said latter period. The cover 16 being adapted to be moved by the operator 70 away from the body 10 simultaneously with a movement of the folded end wall 14 and side walls 15, the package then assuming the appearance shown in Figure 4.

It is obvious that various changes and modifi-

cations may be made in the details of construction and design of the above specifically described embodiment of my invention without departing from the spirit thereof, such changes and modifications being restricted only by the scope of the 5 invention as herein claimed.

What is claimed is:

1. A dispensing package for free flowing material, comprising a closed box body for carrying a quantity of the material and having a top wall 10 with an opening therethrough near one edge of the box body, and a chute portion having foldable end and side walls extending upwardly from the adjacent edge and the corresponding side walls of the box body beyond the said top wall 15 of the box body and having a foldable cover wall spaced from the box body top wall and joining the end and side walls of the chute, said chute being open at its end remote from its end wall and said opening in the top wall of the box body, 20 said cover wall adapted to be forced down upon the top wall of the box body to close the opening therein with the chute walls and edge portions of the cover wall rolled inwardly in underlapping relation to hold the cover wall closed and said cover wall adapted to be pulled out into position to open the chute, whereby the material is retained in the box body when the latter is disposed in upright position and whereby the material flows through said opening in the top wall 30 of the box body into the closed end of the chute when the box body is tilted backwardly from the open end of the chute, and whereby the material in the chute may flow from the open end thereof when the box body is tilted in the direction of the 35 open end of the chute and the remaining material in the box body is trapped therein against said top wall thereof.

2. A dispensing package for free flowing material, comprising a closed box body for carrying a 40 quantity of the material and having a top wall with an opening therethrough near one edge of the box body, and a chute portion having foldable end and side walls extending upwardly from the adjacent edge and the corresponding side walls 45 of the box body beyond the said top wall of the box body and having a foldable cover wall spaced from the box body top wall and joining the end and side walls of the chute, said chute being open at its end remote from its end wall and said opening in the top wall of the box body, said cover wall having a closure tongue on its end at the open end of the chute and said cover wall and the side and end walls of the chute adapted to be rolled and forced downwardly to engage the 50 cover wall against the top wall of the box body and close the opening therein, said tongue adapted to be bent down and sealed against the adjacent edge wall of the box body to hold the cover wall down in closed position, said tongue adapted to be freed from the box body and pulled upwardly to raise the cover wall and open the chute, whereby the material is retained in the box body when the latter is disposed in upright position and whereby the material flows through 55 said opening in the top wall of the box body into the closed end of the chute when the box body is tilted backwardly from the open end of the chute, and whereby the material in the chute may flow from the open end thereof when the box body is 60 tilted in the direction of the open end of the chute and the remaining material in the box body is trapped therein against said top wall thereof.

ORVAL I. KIGHT.
